CHRISTMAS ORNAMENT

Elmer K. Arnold, La Porte, Ind., assignor to The Ove Gnatt Company, Inc., La Porte, Ind., a corporation of Indiana

Application March 8, 1948, Serial No. 144,991

Term of patent 3½ years

(Cl. D29—1)

To all whom it may concern:

Be it known that I, Elmer K. Arnold, a citizen of the United States and a resident of La Porte, in the county of La Porte and State of Indiana, have invented a new, original, and ornamental Design for a Christmas Ornament, of which the following is a specification, reference being had to the accompanying drawing, forming a part hereof, and in which:

Fig. 1 is a front elevational view of a Christmas ornament, showing my new design;

Fig. 2 is a rear elevational view of the same;

Fig. 3 is a side elevational view of the same;

Fig. 4 is a top plan view of the same;

Fig. 5 is a bottom plan view of the same.

I claim:

The ornamental design for a Christmas ornament, as shown.

ELMER K. ARNOLD.
